ANDREW D. DOWD, OF HOBOKEN, NEW JERSEY, ASSIGNOR TO WESTERN ELECTRIC COMPANY, INCORPORATED, OF NEW YORK, N. Y., A CORPORATION OF NEW YORK

MEANS FOR SYNCHRONIZING ROTARY DEVICES

Application filed April 26, 1928, Serial No. 272,900, and in Great Britain October 31, 1927.

This invention relates to means for synchronizing a plurality of rotary members and is particularly intended and adapted for use in so-called synchronous telegraph or 5 signaling systems though also applicable for other apparatus, as for example, the synchronizing of picture transmitting apparatus.

An object of the invention is to maintain 10 in synchronism rotary distributors at terminal stations in a simplex telegraph system having an intermediate station arranged to repeat signals in opposite directions on long submarine cables.

15 A more specific object of the invention is to automatically correct in both forward and backward directions the speed of the distributors at the repeating and the receiving stations during each receiving interval when 20 such distributors pull out of phase with the distributors at the sending station.

A preferred embodiment of the invention is shown and described herein as being adaptable to a multiplex printing submarine cable 25 telegraph system such as disclosed in U. S. Patent No. 1,689,328 granted to A. M. Curtis on Oct. 30, 1928, and therefore a brief description of this system will facilitate a clear 30 understanding of the present invention. In this system a number of separate printing telegraph transmitting and receiving mechanisms at both ends of the cable are connected in rotation so that each transmitting circuit at one end is momentarily connected over the 35 cable to its corresponding receiving circuit at the other end. The amount of time allotted to each circuit is equal to the total transmission time divided by the number of separate sets of circuits. The cable operation is sim- 40 plex, that is, messages are transmitted in one direction only during a given interval of time and the direction of transmission is reversed automatically at stated intervals in order to handle traffic in both directions over 45 one cable. In other words, the transmission mechanisms at one end of the cable are connected to the receiving mechanisms at the opposite end of the cable for a certain period and then reversed so that the transmitting 50 mechanisms at the opposite end are connected

to the receiving mechanisms at the originating end. This reversal of direction of transmission is effected by direction control apparatus operated automatically after having been set to the desired proportions of time. 55 The mechanisms for transmitting and receiving consist of so-called rotary distributors comprising transmitting rings, receiving rings and correcting rings. The correcting rings, which are mounted on each of the 60 sender distributors, are arranged to be orientable in relation to the other rings on their respective distributors whereby the system may be adjusted before the actual transmission of messages begins to establish synchronism between the sender distributor at one end of the cable and the receiving distributor at the other end when such distributors are interconnected for the transmission 65 of messages. In this manner, different 70 amounts of time lag due to the transmission characteristic of the cable may be compensated. The distributors have a tendency to drift out of synchronism and phase during the intervals when the reversals of direction 75 and transmission take place. Means for correcting this loss of synchronism and phase are disclosed in detail in U. S. Patent No. 1,670,461, issued to G. A. Locke on May 22, 1928, which means are particularly adapted 80 to systems having only two stations interconnected by a submarine cable. The rotatable brushes of the distributor at the sending station are arranged to rotate at a slightly faster speed than those of the distributor 85 at the receiving station and, therefore, the correction to be applied in order to maintain the brushes at both stations in synchronism and phase is made at the receiving station, in response to the incoming signals. This 90 correction is generally made in a forward direction, that is, in the direction of rotation of the distributor brushes and, if it should be desirable at any time to effect the correction in a backward direction, a man- 95 ually operated two-position switch which is provided for this purpose must be operated to its alternate position in order to shift the correcting apparatus for backward move- 100 ment of the distributor brushes.

According to the present invention, correcting means somewhat similar to those disclosed in the Locke patent, supra, are employed for restoring synchronism and phase in a system in which two terminal stations and an intermediate station are interconnected by a long submarine cable, but the proposed method of correcting provides for correction in both forward and backward directions automatically during each receiving interval. By the proposed method the rotary distributors at the interconnected stations may be operated at the one speed and, therefore, should the distributors at the receiving terminal station and the intermediate station fall out of synchronism and phase with the distributor at the sending terminal station, the correction can be applied at the receiving terminal station and the intermediate station practically simultaneously.

This invention will be better understood by reference to the following detailed description taken in connection with the accompanying drawing in which Figs. 1 and 2 represent a diagrammatic layout of a multiplex submarine cable telegraph system which includes an inland terminal station A, a land line, a shore terminal station B, a submarine cable, an intermediate, or repeater, station C, another submarine cable, and another terminal station D, all connected in series. Fig. 3 shows the correcting mechanism used in connection with the apparatus at the terminal station D.

Inasmuch as the invention relates principally to a method and means for maintaining in synchronism and phase the distributors at the various stations, such parts of the system as are not directly concerned with the problem, for example, such apparatus as the transmitting and receiving distributors, impulse transmitting and printing devices, driving motors, storing relays, and amplifier units are merely indicated by enclosures, while of the direction of transmission control apparatus, only the cams and spring contacts essential for the switching of the line for transmission in one direction or the other have been indicated. On the other hand, the speed correcting or synchronizing means at the terminal station D have been shown in considerable detail and this will be taken as being representative of similar means used in connection with the receiving equipment at stations A and C. For a full understanding of the system, reference can be made to the Curtis patent, supra, as the following description will be confined principally to such portions of the system as are connected with the synchronizing problem.

Referring to Fig. 1 there is shown at the inland terminal station A, a transmitting distributor 100 with its associated impulse transmitting device 101 and a receiving distributor 102 with its printing device 103 connect-

ed to contacts actuated by cam 104, which cam, under the control of the direction control apparatus (not shown), is adapted to alternately connect said distributors to a land line 105 which extends to the shore terminal station B. Correcting rings 106 with their associated correcting apparatus 107 are shown connected to the contacts of a two-position correction control relay 108 at station B. Relay 108 is shown connected in series with the line relay 109 in the output of amplifier 110 the latter being connected to the submarine cable 111 which extends to the repeater station C.

The equipment at station B comprises a receiving distributor 112 and its associated storing relays 113 from which the signals are retransmitted through the transmitting distributor 114 to the submarine cable 111. Of the direction control apparatus at this station, only transfer relay 115 and the cams 116 and 117 for controlling contacts to switch from reception to transmission, and vice versa, have been shown. At this station, signals received from line 105 are repeated to cable 111 through the receiving distributor 112, storing relays 113, transmitting distributor 114, while the signals from the cable 111 are amplified through the amplifier 110 to actuate line relay 109 which directly controls the retransmission of signals to the land line 105 through the contacts actuated by cam 116. The corrector control relay 108 responds to the signals incoming from cable 111 and thereby causes the necessary correction in the receiving distributor 102 through the correcting rings 106 and correcting apparatus 107. The correcting rings 106 are mounted on the sending distributor 100, and the correcting apparatus 107, which is for producing angular shifts of the brushes traveling over the faces of the distributors 100 and 102, is located between the motor (not shown) for driving the distributors and the distributors themselves, as will hereinafter be explained. The distributors at station B are driven in synchronism with the distributors of station A by means of the distributor arrangement 118 at station A whereby impulses are sent over a separate line 119 to the driving motor arrangement 120 at station B. These arrangements are shown and described in detail in the Curtis patent, supra. No correcting rings or apparatus are required for station B because the distributor thereof is driven from the same source as the distributor at station A.

The submarine cable 111 terminates at repeater station C at which the equipment for receiving signals includes an amplifying device 200, line relay 201, receiving distributor 202, and storing relays 203, and these signals are retransmitted by a sending distributor 204 to a second submarine cable 205 which extends to the terminal station D. The cor-

rection control relay 206 is in series with the line relay 201 and controls the impulses repeated to the correcting rings 207 for the operation of the correcting apparatus 208 to effect the necessary correction in the distributors 202 and 204. Repeating signals in the opposite direction, that is, from station D to A through station C is accomplished by transfer relay 209 and cam 210 and transfer relay 211 and cam 212, all of which are under the control of the direction control apparatus (not shown). The signals incoming from cable 205 are received and amplified by the amplifying device 213 and line relay 214. Relay 214 repeats the amplified signals to receiving distributor 215 and storing relays 216 and these repeated signals are retransmitted through sending distributor 217, over cable 111 and land line 105, to station A. The correction control relay 218 is in series with the line relay 214 to control the impulses repeated to the correcting rings 219 for operating correcting apparatus 220 to effect the necessary correction in the distributors 215 and 217. Two sets of distributors with separate correcting apparatus are provided at station C to handle traffic in both directions, the correcting apparatus 208 being located between the motor (not shown) for driving distributors 202 and 204 and the distributors themselves, and the correcting apparatus 220 being located between the motor (not shown), for driving distributors 215 and 217 and the distributors themselves. The correcting rings 207 and 219 are respectively mounted on the sender distributors 204 and 217.

Submarine cable 205 terminates at station D at which the equipment for receiving signals consists of an amplifying device 221, line relay 222, receiving distributor 223 and the printing apparatus 224. The correction control relay 225 is in series with the line relay 222 to control the correcting apparatus 226 through correcting rings 227. Transmission from station D is directed by impulse transmitting devices 228 through the sending distributor 229 to cable 205 and the direction control cam 230 causes through the operation of transfer relay 231, the shifting of operation over the cable 205 from the receiving to the sending apparatus, and vice versa.

The correcting apparatus 226 and correcting rings 227 in Fig. 2 are shown in detail in Fig. 3 and respectively designated therein by characters 326 and 327. The correcting rings are made up of a continuous ring and a segmented ring, the latter ring consisting of ten segments for each channel employed in the system. For example, in a five-channel system such as described in the Curtis patent, supra, the segmented ring consists of fifty segments. These rings are interconnected by a rotatable brush 332 which, as it passes over each segment is arranged to complete a circuit for operating an auxiliary correction relay 333.

Relay 333 is a three-position relay and controls the operation of a correcting mechanism 334. This mechanism is located between the motor (not shown) for driving the distributors 323 and 329 and the distributors themselves. The shaft 335 is driven by the motor and the shaft 336 drives the arms on which the brushes, such as 332, for the distributors are mounted. These arms are arranged to drive the brushes over the various distributor faces in a manner well known in the art. The correcting mechanism 334 consists of a differential beveled gear arrangement 337 disposed between the motor shaft 335 and the brush shaft 336 and the gears that link these two shafts together are mounted on a supporting frame 338 secured to a worm pinion 339 that meshes with a worm 340. Any change in the angular position of the worm pinion 339 changes the angular position of the linking gears and this in turn changes the angular position of the brush shaft 336 with respect to the motor shaft 335. The worm 340 is rotatable to shift the angular position of the worm pinion a small angle by means of corrector magnets 341 and 342 in one direction or the other. The ratchet wheel and pawl mechanisms 343 and 344, respectively, are operated by these magnets so that upon the operation of either one of the magnets, an angular shift of the distributor brushes in one direction or the other is effective. In order to hold the worm 340 firmly while the magnets are not rotating it, a separate ratchet wheel 345 and a pawl 346 is provided. This wheel and pawl also limits the movement of the worm 340 to one step each time a corrector magnet operates. The automatic corrector mechanism 334 is therefore capable of shifting the brushes of the distributors in a forward or in a backward direction, magnet 341 being provided for shifting them in a forward direction and magnet 342 for shifting them in a backward direction. By forward direction is meant a shift in the same direction as the rotation of the brushes; by backward is meant a shift opposite to the direction of rotation of the brushes. It is seen, therefore, that this mechanism corrects in either direction and can be effective while the distributor brushes are being rotated by the motor and in this way synchronizing effects may be produced between the brushes of the distributors at the different stations, as will hereinafter be more fully explained. The automatic correcting apparatus at stations A and C are identical with that shown in Fig. 3, two sets being provided for station C in order to correct for synchronism and phase in opposite directions.

To more fully set forth the various features of this invention, a description will now be made of the method of bringing the distributors at the various stations into synchronism before the actual transmission of mes-

sages takes place. The first operation in lining-up the system is to determine the speed at which the distributors are to be operated. The system may primarily be controlled from station A and the speed of the distributors at stations B, C and D may be regulated in accordance with the determined speed of the distributor at station A. That is to say, the fundamental speed will be set at station A although it should be remembered that during the transmission of messages the station from which transmission takes place at any given time sets the pace at which the receiving station distributors will operate. As previously mentioned, the speed of the distributor at station B is controlled by the distributor drive rings 118 at station A and will not be described herein in detail as their arrangement is well known in the art. It is sufficient to say that the speed of the motor for driving the distributors at station B is entirely controlled from the impulses received over the line 119. If, therefore, the distributors of station A are set to a certain speed and the motor at station B is regulated so that the distributors at station B are traveling at the same speed, the next step will be to transmit so-called phasing signals from the sending distributor 100 over line 105 to the receiving distributor 112 at station B. The brushes of the receiving distributor 112 must now be set in phase with the brushes of the sending distributor 100 at station A. This is done by means shown and described in detail in the Curtis patent, supra, and is described in general in the Locke patent, supra. When this phase relation is attained, the signals received from station A are permitted to be retransmitted through storing relays 113 and the sending distributor 114 over the submarine cable 111 to station C. These retransmitted signals are now used by the operator at station C for determining the speed at which the distributors at station C shall travel and, as far as transmission of signals between stations A and C are concerned, the presence of station B may be disregarded in the following description of the method of synchronizing.

The operator at station C now proceeds in a manner similar to that of the operator at station B in phasing the brushes of the receiving distributor 202 and, when this phase relation has been obtained, the correcting apparatus 208 is switched in to be controlled by the impulses produced by the corrector control relay 206. The correcting apparatus will function to automatically correct the positions of the distributor brushes in both forward and backward directions for any loss of synchronism or phase occurring thereafter. The signals received at station C are retransmitted through storing relays 203, sending distributor 204 over submarine cable 205

to station D. These signals are used by the operator at station D for determining the speed at which the distributors at station D shall travel. The operator at station D also proceeds in a manner similar to that of the operator at station B and, when the brushes of the receiving distributor 223 are brought into phase with the brushes of sending distributor 204 at station C, the operator at station D switches in the correcting apparatus 226 to be controlled by the impulses produced at the correction control relay 225 in response to the incoming signals. Correcting apparatus 226 will likewise function to automatically correct the positions of the distributor brushes at station D in both forward and backward directions for any loss of synchronism or phase.

In order to reverse the direction of transmission and reception so that messages may be transmitted from station D, the direction control cams 104, 116, 117, 210, 212 and 230 are actuated by a timing device (not shown). This timing device is merely a means for actuating the above mentioned cams at certain intervals to make them perform this desired switching of the circuits at predetermined intervals. A device of this kind is disclosed in U. S. Patent No. 1,681,489 granted to G. A. Locke and H. H. Haglund on Aug. 21, 1928. It is sufficient to mention that the cams at all four stations are controlled to perform their switching operations substantially simultaneously with due regard to lag in transmission. Cam 104 causes the contacts to open the connections between sender distributor 100 and line 105 and to close the connections between the receiving distributor 102 and the line 105. Similarly, cam 116 opens the connections between the receiving distributor 112 and line 105 and closes connections between line 105 and the armature of line relay 109. The cam 117 closes a circuit for the operation of relay 115 to open the connection between the submarine cable 111 and the sending distributor 114 and to close a connection between this cable and the amplifying device 110. Signals incoming over cable 111 will therefore now pass as previously stated through the amplifying device 110, line relay 109 and correction control relay 109. The operation of cam 210 closes a circuit for the operation of transfer relay 209 to cause this relay to actuate its armature to a position opposite to that shown in the drawing, thereby opening the connection between cable 111 and the amplifying device 200 and closing a connection between the cable and the sending distributor 217. Cam 212, upon operating, closes a circuit for the operation of transfer relay 211 to cause this relay to open the connection between the cable 205 and the sending distributor 204 and to close a connection between the cable and amplifying device 213 at which de-

vice the signals are amplified sufficiently to operate line relay 214 which, in turn, repeats the signals to the receiving distributor 215 and storing relays 216 for retransmission through sending distributor 217. The operation of cam 230 operates transfer relay 231 to open the connection between cable 205 and receiving apparatus at station D and to close a connection between the cable and the sending distributor 229.

When the operations of the aforementioned cams are completed, the transmission of phasing signals from station D through repeater stations C and B to station A may now begin for synchronizing of the distributors at station C, B and A to the speed of the distributor at station D. It will be recalled that the arrangement of the system is such that the sending station is a pace-setting station although the distributors at all four stations are operating at the one speed. When the phasing is accomplished at each station in turn, the correcting apparatus at the repeating station C and the receiving station A are connected for maintaining the distributors at their respective stations in synchronism and phase.

Fig. 3 shows the equipment at station D more in detail than Fig. 2, different characters being used for corresponding elements to avoid confusion in referring to the two figures. The correcting rings 327 are shown connected through the continuous, or upper, ring to the contacts of the correction control relay 325. Relay 325 is a two-position polarized relay having an armature arranged to remain in one position while signals of one polarity are being received and to move to its alternate position when the polarity of the signals is reversed. The segmented ring of ring set 327 is arranged in two groups of alternate segments, one group A being connected in a circuit extending through the left-hand winding of auxiliary correction relay 333 and the other group R connected in a circuit extending through the right-hand winding of relay 333. Relay 333 is a three-position polarized relay having an armature arranged to be normally in a neutral position but effective to engage either of two associated contacts in response to a current flowing through either of the above mentioned windings. When the armature of relay 333 engages either of its associated contacts, one or the other of the corrector magnets 341 and 342 operates to move the brushes on the distributors 229 and 223 in Fig. 2 in either a forward or a backward direction, the direction depending on which winding of relay 333 is energized. When rotatable brush 332, which interconnects the rings of ring set 327, is in contact with an A segment at the instant relay 325 moves from one contact to the other, the left-hand winding of relay 333 becomes energized, operating corrector magnet 341 to

move the brushes in a forward direction and when the brush is in contact with an R segment the right-hand winding of relay 333 becomes energized and the magnet 342 operates to move the brushes in a backward direction. It will be seen, therefore, that the brush correction is in a forward or a backward direction according as the brush 332 is in contact with an A (advance) or R (retard) segment; and if, as will be the case if the distributors of station D are in perfect phase relation with the distributors of station C, the brush 332 is passing over one of the insulated spaces between an A and an R segment at the instant of the actuation of relay 325, no circuit will be completed to either of the windings of relay 333. Assuming that the brushes of the distributor of station D are lagging behind the brushes of the distributor at station C taking into consideration the characteristic lag of the cable 305, brush 332 will be in contact with an A segment as shown instead of in contact with the insulated space following it, and a circuit is therefore closed, traceable from positive battery 347, armature and right-hand contact of relay 325, condenser 348 and high resistance 349 in parallel, conductor 350, continuous ring, brush 332, and an A segment of ring set 327, conductor 351, back contact and armature of magnet 341, conductor 352, left-hand winding of relay 333, to negative battery 353, but not enough current will flow in this circuit at this time because of the high resistance in parallel to the condenser 348. At the next reversal of polarity of the incoming signals, the armature of relay 325 moves to its alternate position and closes a circuit extending from the positive battery 347, armature and left-hand contact of relay 325, condenser 354 and high resistance 355 in parallel, conductor 350 over the same path just traced to the negative battery 353. A surge of current is produced in the circuit including condenser 354 at the moment the armature and left-hand contact of relay 325 interconnect, and this surge is sufficient to operate relay 333. Relay 333 closes a circuit traceable from positive battery 356, armature and left contacts of relay 333, conductor 357 through the winding of magnet 341 to negative battery and magnet 341 operates. Magnet 341, in operating, actuates the pawl and ratchet mechanism 343 to shift, through the corrector mechanism 326, the shaft 336 for a small angular distance in a forward direction in relation to the rotation of the shaft. This shifting of shaft 336 causes the brushes of the receiving distributor 323 and brush 332 of the correcting rings 327 to move forward a corresponding angular distance. When relay 333 operates, it closes at its left contact and armature a locking circuit for itself extending over conductor 357, resistance 358, through the left-hand winding of relay 333 to negative bat- 130

tery 353, and this locking circuit prevents the release of the relay until magnet 341 has reached its fully operated position. When magnet 341 reaches its fully operated position, a circuit is closed extending from positive battery 356, armature and left contact of relay 333, conductor 357, resistance 358, armature and front contact of magnet 341, conductor 359, to negative battery 353, and this circuit shunts the left-hand winding of relay 333 which now releases its armature, thereby causing the release of magnet 341. In this manner relay 333 is prevented from operating in response to another impulse received from the correcting rings until the magnet 341 is fully restored to its normal position. At the next reversal of polarity of the incoming signals passing through the windings of relay 325, a brush will again be in contact with an A segment if synchronism or phase has not been restored, and the relay armature will move to its right-hand contact to send another impulse from positive battery 347 through the left-hand winding of relay 333. Relay 333 will again operate and cause the correcting mechanism 336 to move the distributor brushes another step in a forward direction. Resistance 358 is of a value such that the holding current passing therethrough and through the left-hand winding of relay 333 is not sufficient to prevent the release of the relay when magnet 341 engages its front contacts. This operation is repeated until synchronism and phase are restored.

Should the brushes of the distributors at station D run ahead of those at the other stations, the brush 332 would make contact with an R segment every time an incoming signal is received in relay 325, and for each reversal of polarity the armature of relay 325 would move to its opposite contacts. Thus, an impulse of positive current is sent on each reversal through the condensers 348 and 354 alternately and through an R segment, providing relay 333 is in its normal position, to operate corrector magnet 342 over a circuit extending from positive battery 347, through either condenser 348 or 364 and an R segment, back contact and armature of magnet 342, conductor 360, through the right-hand winding of relay 333 to negative battery 353. Relay 333 operates and interconnects its armature and right-hand contact to close a circuit extending from positive battery 356, armature and right contact of the relay, conductor 361, through the winding of magnet 342 to negative battery. Magnet 342 operates and actuates the pawl and ratchet mechanism 344 to shift the shaft 336 for a small angular distance in a backward direction in relation to the rotation of the shaft. This shift of the shaft causes the brushes of the receiving distributor 323 and brush 332 of the correcting ring 337 to move backward a corresponding angular distance.

As previously stated when relay 333 operates, it closes a locking circuit for itself, but this circuit is now traceable over the right contact of the relay, resistance 362, and through the right-hand winding of the relay to the negative battery 353. Relay 333 is prevented from reoperating in response to subsequent impulses from positive battery 347 until magnet 342 has been restored to its normal position. The resistance 362 is the same value as resistance 358 and the holding current passing therethrough and the left-hand winding of relay 333 is not sufficient to prevent the release of the relay when the armature of magnet 342 engages the front contact of the relay.

Inasmuch as the correcting apparatus at stations A and C are identical with that shown in Fig. 3, their operations will be the same as those for the apparatus at station D. No further description will be necessary. By this method of correction the motors at all the stations in the system may be operated at the one speed, and for any loss of synchronism or phase which may occur in the intervals at reversals in transmission to reception and vice versa, when no impulses are being transmitted, the correcting mechanisms at the receiving stations may automatically shift the brushes of their respectively associated distributors in both forward and backward directions during each receiving interval.

What is claimed is:

1. In a synchronous telegraph system, a transmission line, distributors and brushes therefor connected to opposite ends of said line; synchronizing means for said distributors controlled by the distributor at the sending end of said line, means for stepping the brushes around the distributor at the receiving end in both forward and backward directions with respect to the direction of rotation, automatic means for effecting the change of brush stepping from one direction to the other, and means for completing each step of said brush before the second mentioned means is permitted to again operate.

2. In a synchronous telegraph system, a plurality of stations connected in series, distributors and rotating brushes therefor arranged to operate at the one speed, a transmission line interconnecting said stations, means for automatically reversing the direction of transmission from time to time, synchronizing means at each of said stations comprising a plurality of correcting clock-hand mechanisms for stepping the distributor brushes in both forward and backward directions with respect to the direction of rotation, in response to the current reversals of the incoming signals should the distributors at the receiving stations pull out of phase with the distributor at the sending station and automatic means for reversing the brush

stepping operation should the brush be stepped beyond its desired phase.

3. In a synchronous telegraph system, a transmission line, a rotary distributor comprising a continuous and a segmented ring and associated with said line, a rotatable brush interconnecting said rings, two electrically controlled clockhand mechanisms for stepping said brush in response to reversals of current of the incoming signals in forward and backward directions with respect to the direction of rotation while it is rotating, to vary the speed of said brush in accordance with the speed of the incoming signals, automatic means for changing the direction of said stepping operation and means for preventing the further operation of either mechanism until such mechanism is positively restored to its normal position.
- 20 4. In a synchronous telegraph system, a transmission line adapted for simplex operation, a rotary distributor comprising a continuous and a segmented ring associated with said line, a rotatable brush interconnecting said rings, two electrically controlled clockhand mechanisms for automatically stepping said brush in response to reversals of current of the incoming signals, in both forward and backward directions with respect to the direction of rotation while it is rotating, to vary the speed of said brush in accordance with the speed of the incoming signals, a two-position relay in series with said line and responsive to current reversals of the incoming signals, a three-position relay for operating either of said mechanisms, a circuit for operating the second mentioned relay should said brush be out of phase with the incoming signals, and means in said circuit for preventing the reoperation of said second relay until said mechanisms are fully restored to their normal positions.

In witness whereof, I hereunto subscribe my name this 25th day of April A. D., 1928.

45 ANDREW D. DOWD.
